CONTAINER CLOSURE OR THE LIKE

James B. Swett, Barrington, and Jack V. Croyle, Woonsocket, R.I., assignors to Dart Industries Inc., Los Angeles, Calif.

Filed Aug. 27, 1970, Ser. No. 24,724

Term of patent 14 years

Int. Cl. D7—01

U.S. Cl. D44—1

FIG. 1

FIG. 3

FIG. 1 is a top perspective view of a container closure or the like showing our new design;

FIG. 2 is a reduced scale bottom plan view thereof; and

FIG. 3 is a top perspective view of a container closure or the like showing another form of our new design.

We claim:

The ornamental design for a container closure or the like, substantially as shown and described.
